WELL TOOLS

Herbert C. Otis, Dallas, Tex., assignor to Otis Engineering Corporation, Dallas, Tex., a corporation of Delaware

Filed Nov. 14, 1958, Ser. No. 773,919
11 Claims. (Cl. 103—232)

This invention relates to well tools and more particularly, to a well tool for removing fluids from the bores of wells by gas pressure.

An object of the invention is to provide a new and improved well tool for removing liquids produced by wells which is removably positionable in the well tubing of a well.

Still another object is to provide a well tool for removing well fluids from wells which produce both gas and liquids, the gas being conducted to the surface of the well through the annular flow passage between the well casing and an inner well tubing, the liquid being conducted to the surface through the well tubing, and the well tool being positionable in the well tubing.

A further object is to provide a well tool for automatically removing liquid from the bore of a well which produces both gas and liquids and wherein the liquid column in the well acts in controlling operation of the valve and the gas produced by the well provides the motive power for transporting the liquids to the surface.

A still further object of the invention is to provide a well tool for use in wells having a casing and an inner tubing telescoped therein, and wherein gas is produced through the annular space between the tubing and casing which tool includes a valve removably positioned in the tubing and operable by fluids produced in the well, which opens intermittently to permit flow of the gas produced in the well to transport excess liquids to the surface through the well tubing.

Another object is to provide a valve which is positionable in a tubular member, such as well tubing, and which includes a valve sleeve biased downwardly toward an open position by a resilient means and which is moved upwardly toward a closed position by the fluid pressure in the well tubing.

Still another object of the invention is to provide a valve body connectable in a well tubing and having a plurality of restricted orifices opening into the well tubing and a valve sleeve movable upwardly in the valve body by fluid pressure for closing the valve to close such orifices, the valve sleeve being moved toward such closed position by the pressure of fluids in the well tubing in which the valve is positionable.

A further object of the invention is to provide a valve wherein the liquid which passes through the valve sleeve to the well tubing causes the valve sleeve to open when a predetermined pressure is developed by the column of liquid in the tubing above the valve sleeve, the gas flowing through the restricted orifices blowing the liquid upwardly through the tubing to the surface.

A still further object of this invention is to provide a well tool for removing accumulated fluid from the well bore at periodic intervals of time, such intervals being determined by the amounts of liquids produced by the well.

A still further object of the invention is to provide a well tool for removing accumulated fluid from a well bore which is mountable wholly within the well bore.

Additional objects and advantages of the invention will be readily apparent from the reading of the following description of a device constructed in accordance with the invention, and reference to the accompanying drawings thereof, wherein:

FIGURE 1 is a vertical, partly sectional view of the

2

well tool for removing fluids from a well shown removably positioned in the well tubing of a well;

FIGURE 2 is an enlarged, vertical partly sectional view of the valve illustrated in FIGURE 1, showing the valve sleeve in its upper closed position;

FIGURE 3 is a view similar to FIGURE 2, showing the valve sleeve in open position; and

FIGURE 4 is an enlarged fragmentary sectional view of the valve seat, valve sleeve and orifice restricting plug of the valve illustrated in FIGURES 2 and 3.

Referring now to the drawing, the well tool 10 for removing fluids from a well bore is shown anchored in a well tubing 12 by means of a hanger and sealing tool 13 to which it is secured. The tubing 12 extends through the well casing 14 spaced therefrom so that the tubing and the casing provide an annulus or cylindrical flow passage 15 through which the gas and liquid produced from a producing formation 17 may flow. The casing 14 has a plurality of perforations 18 connecting with the flow passage 15 and the producing formation. It will be apparent that the liquid produced by the well is heavier than the gas and will tend to fall downwardly through the annulus 15 to the bottom of the well bore to accumulate therein while the gas may flow upwardly through the annulus 15 to the surface of the well where it is discharged into a storage tank or into a pipe line for transport to the site of use. The well tool 10 is employed to remove such accumulations of liquid through the well tubing 12. The liquid may be either oil or water.

The hanger and sealing tool 13 may be of the type disclosed in the patent to H. C. Otis, No. 1,972,791, and includes a central tubular mandrel 20 which is provided at its lower end with a cup-type sealing member 27 which is moved by fluid pressure into engagement with the tubing to seal between the central tubular mandrel 20 and the tubing. The tubular mandrel is provided with a downwardly and outwardly flared frusto-conical camming surface 30 on which the serrated gripping slips 32 are longitudinally movable. The slips 32 are provided with upwardly extending shanks 33 by means of which they are swingably hung from a slip carrier 34. The slips are held against undue outward displacement by a retainer ring 35 mounted on an external annular flange on the mandrel at the upper end of the expander surface 30.

The hanger and sealing tool 13 is lowerable through the tubing by means of a suitable running tool, not shown, which is connected to the upper end of the slip carrier 34, the gripping slips being thus held in an upper position on the expander surface of central tubular mandrel 20 whereby they are supported in retracted position out of engagement with the internal walls of the tubing during downward movement of the hanger and sealing tool 13.

The slip carrier sleeve 34 and the slips 32 are longitudinally movable on the central tubular mandrel 20 so that when the hanger and sealing means reaches the desired position in the well tubing 12, the running tool is suddenly moved downwardly relative to the mandrel 20 to cause the slips to move downwardly on the expander surface 30 and thus cause their serrated outer surfaces to engage the internal walls of the well tubing to anchor the hanger and sealing means in place in the well tubing. Further downward force is then imparted to the slip carrier to positively anchor the slips in gripping position in the well tubing. The sealing member 27, being fluid pressure expandable, seals against the internal wall of the tubing upon upward fluid flow in such tubing, and, as a result, the seal member 27 seals between the central tubular mandrel 20 and the well tubing so that fluids may now flow from below the hanger

and sealing means 13 only through the tubular bore 37 of the central tubular mandrel.

The lower end 22 of the mandrel 20 is externally threaded whereby the valve 10 may be secured thereto and be supported by the hanger and sealing means 13 in the well tubing.

The valve 10 includes an upper sub 40 having an internally threaded upper end which engages the externally threaded lower end 22 of the tool 13. The upper sub 40 is provided with an externally threaded and reduced lower end on which is threaded the upper end of a valve body 42 into whose lower end is threaded the upper end of the pipe 43. The pipe 43 in turn is connected to a strainer 45 by means of a connector coupling 46. The strainer 45 is preferably of a porous type of metal which permits liquids and gas to pass therethrough but which will not pass solids. The coupling 46 sealingly engages the lower end of the pipe 43 and the upper threaded end of the connector sub 48 of the strainer 45.

The upper sub 40 has an enlarged bore at its lower end which provides a downwardly facing annular shoulder 50 which limits upward movement of the annular valve seat 52 disposed in the enlarged bore and held therein by a snap retainer ring 53. The snap ring is disposed in an internal annular recess 54 of the upper sub 40 located below the downwardly facing shoulder 50 thereof. The annular valve seat 52 is provided with an external annular recess in which is disposed an O-ring or other annular sealing member 56 which seals between the valve seat 52 and the upper sub 40.

The valve body 42 is provided with an internal annular flange 58 which provides a downwardly and inwardly extending upper surface 59 and an abrupt downwardly facing annular shoulder 60. The upper surface 59 of the flange 58 of the valve body 42 limits downward movement of a valve sleeve 62 which is slideable longitudinally in the valve body between an upper position in which its upper end engages the seat 52 and a lower position in which the valve sleeve is supported by said flange 58, since the valve sleeve is provided at its upper end with an external annular flange 63 whose lower shoulder is adapted to engage the upper surface 59 of the flange 58 upon downward movement of the valve sleeve in the valve body.

The valve sleeve is provided with an external annular recess spaced below the flange 63 in which is disposed an O-ring 65 which engages the flange 58 to seal between the valve sleeve and the valve body.

The valve sleeve 62 is biased downwardly toward the open position illustrated in FIGURE 3, by means of a spring 70 disposed about the valve sleeve, the upper end of the spring abutting the downwardly facing annular shoulder 60 of the flange 58 and the lower end of the spring engaging a jam nut 72 threaded on the lower end of the valve sleeve. A similar nut 73 may be threaded on the valve sleeve to lock the upper nut 72 in any adjusted position on the valve sleeve. It will be apparent that the biasing force exerted by the resilient spring 70 may be adjusted by rotation of the nuts 72 and 73 on the valve sleeve 62.

The lower end of the valve sleeve is provided with a choke 75 which is threaded into the lower end of the valve sleeve. The choke limits the effective orifice of the valve sleeve, and the orifice of the choke is smaller than the diameter of the bore of the valve sleeve.

The valve body 42 is provided with a plurality of upwardly and inwardly extending radially spaced lateral ports 80 threaded to receive plugs 82 which have restricted orifices 83a therethrough. The ports 80 open through the upper surface 59 of the internal flanges 58 of the valve body so that the ports 80 provide a flow passage or communication between the exterior of the valve body below the sealing member 27 of the hanger and sealing means or well tool 13 and the interior of the

valve body below the annular valve seat 52 but above the flange 53, so that fluids may flow from the tubing through the ports 80 into the interior of the sub 40 and thence to the longitudinal bore 37 of the hanger and sealing tool and the tubing thereabove, when the valve sleeve is in the lower position illustrated in FIGURE 3. When the valve sleeve is in its upper closed position wherein its upper outwardly and downwardly extending surface 83 abuts the valve seat 52, the valve sleeve 62 prevents flow of fluids through the ports 80 into the longitudinal bore 37 of the hanger and sealing well tool 13.

When the valve sleeve is in the upper position illustrated in FIGURE 2, upward pressure of fluids in the pipe 43 and valve body 42 acts on an area of the valve sleeve 62 which is the difference between the area of the orifice of the choke 75 and the area sealed off by the engagement of the valve seat 52 and the surface 83 of the valve sleeve. The pressure of the fluids in the tubing below the sealing member 27, which is transmitted to the bore of the valve body 42 adjacent the end of the valve sleeve through the ports 80, does not tend to move the valve sleeve either upwardly or downwardly when the valve is in the closed position illustrated in FIGURE 2 since the areas of the flanged head 63 at the upper end of the valve sleeve exposed to such pressure are balanced and provide no unbalanced exposed area upon which such pressure might act to move the valve sleeve in either direction.

When the valve moves to the lower position illustrated in FIGURE 3, however, the well fluids flowing through the ports 80 tend to balance the fluid pressures acting on the valve sleeve so that the force of the spring 70 moves the valve sleeve downwardly.

In use, fluids, both gas and liquid, from the producing formation 17 flow into the well casing 14 through the perforations 18. The gas flows into the annulus or cylindrical flow passage 15 to the surface of the well where it accumulates and may be conducted through suitable lateral flow pipes to a gas transmission line or storage tanks. The liquid which flows into the annulus 15 from the producing formation 17 being heavy falls downwardly to the bottom of the well and as it accumulates therein is forced upwardly into the lower end of the well tubing 12 by the formation pressure. The pressure of the liquids acting upwardly across the choke 75 of the valve sleeve 62 causes the valve sleeve to move upwardly to the closed position against the resistance of the spring 70. The accumulated liquid continues to move upwardly through the choke and the valve sleeve to the longitudinal passage 37 of the hanger and sealing well tool 13 and thence upwardly to the well tubing above the sealing member 27.

When a column of liquid of predetermined height has accumulated or built up in the well tubing above the sealing member 27 and above the valve sleeve 62, the upward pressure differential across the valve sleeve falls or is reduced due to the back pressure created by the weight of such column of liquid standing above the valve in the well tubing, whereupon the valve sleeve moves downwardly to the open position illustrated in FIGURE 3. When this occurs, the pressure of the gas in the annulus 15 forces any remaining liquids in the tubing below the valve ports 80 upwardly through the restricted orifices 83a of the plugs 82 and through the longitudinal passage 37 of the hanger and sealing well tool 13 to the well tubing thereabove. The gas from the annulus now flows not only through the choke 75 of the valve sleeve but also through the additional openings provided by the plug orifices 83a, so that the increased flow of gas from the annulus produces a greater upwardly acting pressure in the well tubing above the valve sleeve which causes the column of liquid in the well tubing to be slugged or moved in a body upwardly through the well tubing to the surface of the well. As the raised column of liquid is discharged through the upper end of the tubing, the upward pressure differential across the valve sleeve is increased due to the fact that the weight of the column of liquid in the tubing

is reduced by virtue of the lessening height of the column of such liquids present in the tubing, and because the combined areas of the openings through the plugs 82 and through the choke 75 are selected to provide an effective flow opening which sufficiently restricts or limits flow of gas therethrough into the tubing above the tool 10 to create an upward differential acting across the valve sleeve 62 to move the same upwardly to closed position at or slightly before the time at which the liquid is completely ejected from the upper end of the tubing. The increased pressure differential created by the gas passing through the valve sleeve will thus again cause it to move upwardly to the closed position when the back pressure created by the column of liquid diminishes due to the fact that the liquid is discharged to the surface of the well. When the valve sleeve moves again to its closed position, liquid again begins to accumulate in the bottom of the well tubing, until a predetermined column of liquid of the predetermined height above the valve is again built up in the well tubing, which again causes the valve sleeve to move 20 to its lower position whereby the gas admitted through the orifices 82a as well as through the choke orifice 75 again causes the column of liquid to be discharged through the upper end of the tubing at the surface of the well.

It is preferable that the valve sleeve move to its upper or closed position at a time slightly before the entire column of liquid in the tubing has been ejected therefrom, because the gas present in the tubing above the tool 10 will continue to expand, since it is acting against only atmospheric or a very low back pressure at the surface, and such continued expansion of the gas will force out of the tubing the short column of liquid still remaining in the upper end of the tubing after valve sleeve closes. This operation reduces the amount of gas used in slugging the liquid out of the tubing, and is desirable. However, the sizes of the orifices in the plugs 82 and in the choke 75 may be so selected that they provide, in toto, an opening which creates a restriction limiting flow of gas therethrough sufficiently to close the valve sleeve when all liquid has been ejected from the tubing above the tool.

It will now be seen that the valve acts automatically intermittently to utilize the gas entering the well bore from the producing formation of the well to discharge accumulated liquids through the well tubing in a slug, with minimum wastage of gas.

It will further be seen that the valve includes a valve sleeve having a restricted orifice which restricts flow of well fluids flowing therethrough to create a predetermined pressure differential thereacross, and that such differential moves the valve sleeve to an upper position against the biasing force of a spring 70. It will further be seen that the pressure differential is reduced or decreased by the back pressure created by liquids forced or flowing upwardly through the valve until a predetermined back pressure, created by a predetermined column of liquid above the valve in the well tubing in which the valve is located, is attained, whereupon the valve opens to permit the gas from the producing formation to act upon the column of liquid in the well tubing to move it upwardly in the well tubing to be discharged at the surface of the well.

It will further be seen that the effective orifice of the valve sleeve may be varied by connecting chokes 75 of preselected orifices in the sleeve; and, similarly, that the effective orifice provided by the orifices 82a in the plugs 82 may likewise be varied to vary the conditions under 65 which the valve closes.

The orifice of the choke 75 should be such that, at the differential existing across the choke between the bottom hole well fluid pressure therebelow and the substantially atmospheric pressure in the tubing thereabove, the choke will permit liquid to pass therethrough at a rate somewhat less than the rate at which liquid is accumulating in the well bore from the producing formation. Under this condition, substantially no gas will accompany the liquid through the choke, but liquid will accumulate

in the bottom of the well in the tubing and in the annulus.

Also, the orifices 82a in the plugs 82, in toto, should provide an effective orifice of a sufficient capacity to permit passage of gas therethrough at a high enough rate to provide an adequate volume of gas in the tubing to "slug" the liquid column out of the upper end of the well tubing, but must, as has already been pointed out, also be of a size which will restrict or limit flow of gas therethrough sufficiently to effect closing movement of the valve sleeve 10 when the liquid has been ejected.

It will further be seen that the predetermined height of the column of liquid in the well tubing, which causes actuation of the valve, may also be varied by varying the downwardly biasing force exerted by the spring 70 by adjustment of the nuts 72 and 73 on the valve sleeve to vary the force with which the spring 70 biases the valve toward open position.

It will likewise be seen that the valve operates automatically without control from the surface once it has been installed in the well tubing.

It will also be apparent that the valve 10 may be located in the well tubing by any suitable hanger and sealing tool, such as the well tool 13 provided with anchoring means 32 which lock it in position against upward displacement in the well tubing and with a sealing member 27 which seals above the valve, whereby all flow of well fluids takes place through the valve sleeve when the valve sleeve is in its upper closed position, and through the valve sleeve and the lateral ports 80 of the valve body when the valve sleeve is in its lower open position.

It will further be seen that the new and improved well tool for automatically intermittently removing liquids from a well includes an outer tubular member mounted in a well flow conductor of the well having a valve longitudinally movably mounted in the bore thereof provided with a restricted flow passage so that the liquids will pass therethrough with substantially no gas, and that the valve is adjustable in such a manner that the accumulated column of liquid in the tubing acts to control the opening of the valve sleeve to utilize the gas from the producing formation to slug or eject the liquid as a body from the tubing when a sufficient column of liquid of predetermined height is in the conductor above the valve member, and that the outer member is provided with a lateral port or ports which, when the valve moves toward an open position, utilizes flowing therethrough to effect reclosing of the valve sleeve to permit further accumulation of liquid preparatory to a rejection of the slugging ejection of such liquid.

It will further be seen that when the well liquid is discharged from the upper end of the well flow conductor the increased pressure differential across the valve member moves it upwardly to its closed position whereby an automatic intermittent movement of the valve member is obtained which causes intermittent discharges of the accumulated well fluids from the well.

It will be readily apparent that the well tool may be used equally well for producing liquids from a well bore in which the gas pressure is injected into the annular space between the casing and the tubing from an external source, as, for example, by introducing gas at the surface from another well or a compressor or the like. Such an installation is common in the gas lifting of oil and gas wells to provide a supply of lifting gas pressure in the annular space for lifting fluids therefrom and would be used in cases in which the well from which the liquids are to be produced does not itself produce sufficient gas from the producing zone into the well bore to lift the liquid to the surface.

The foregoing description of the invention is explanatory only, and changes in the details of the construction illustrated may be made by those skilled in the art, within the scope of the appended claims, without departing from the spirit of the invention.

What is claimed and desired to be secured by Letters Patent is:

1. A well tool including: an outer elongate member having a longitudinal bore; a valve sleeve having a continuously open longitudinal passage in said longitudinal bore of said outer member for limited longitudinal movement therein; means sealing between said valve sleeve and said outer member for preventing flow of fluids therebetween, said longitudinal flow passage of said valve sleeve permitting flow of fluids through said outer member past said sealing means at all times, said outer member having a lateral port communicating with said longitudinal bore above said sealing means, said valve sleeve when in an upper position closing said port, said valve sleeve permitting flow of well fluids through said port into said longitudinal bore when in a lower open position; and means engaging said valve sleeve in said outer member biasing said valve sleeve toward open position, said valve sleeve having a means restricting said flow passage, said means restricting flow through said flow passage creating a predetermined fluid pressure differential across said valve sleeve for moving said valve sleeve between a position closing said lateral port and a position opening said lateral port in response to the differential in fluid pressures above and below said valve sleeve.

2. A well tool for intermittently removing well fluids, which include liquids, from a well provided with a well flow conductor including: an outer member having a longitudinal flow passage therethrough; means connected with said outer member for releasably securing said outer member in the well flow conductor; sealing means carried by said outer member for sealing between said outer member and said well flow conductor; said outer member having a lateral port below said sealing means providing for admission of fluids from within the well flow conductor exteriorly of said outer member into the interior thereof; a valve element in said longitudinal flow passage of said outer member longitudinally movable therein; sealing means in said outer member below said lateral port and engaging said valve element for preventing flow of fluids through said outer member exteriorly of said valve element; said valve element being movable longitudinally in said outer member between a port closing position wherein it closes said lateral port and an open position wherein said port is opened to afford communication between the longitudinal bore of the outer member and the longitudinal bore of the flow conductor, flow restricting means removably positioned in the flow passage of said valve element for controlling the flow of fluids through the said flow passage to create a pressure differential across said valve element, said valve element having a longitudinal flow passage therethrough constantly open to permit continuous flow of fluids through said element, whereby the fluids in the outer member flowing through the valve element act thereupon to move the valve element longitudinally in the outer member, said valve element being movable to said port closing position by the pressure of well fluids flowing through said longitudinal flow passage of said outer member, said valve element being movable to its open position when liquids flowing through the outer member exert a predetermined back pressure on said valve element wherein the opening of said lateral port causes said well fluids flowing through said lateral port and said longitudinal passage of said valve element to move said liquids upwardly in said outer member above said valve element.

3. A well tool of the character set forth in claim 2 which includes means in said outer member biasing said valve element toward its open position in said outer member and resisting movement of said valve element toward position closing said lateral port.

4. A well tool of the character set forth in claim 2 wherein said flow restricting means mounted in the flow passage of said valve element is removably mounted in

said longitudinal constantly open flow passage restricting flow of fluids through said valve element, whereby restriction of flow of fluids through said element may be varied.

5. A well control device for use in a well having a well casing and a tubing string mounted in the casing and having a fluid inlet at its lower end, said well control device including: a valve body having a longitudinal flow passage therethrough and a lateral port intermediate its ends communicating between the exterior of the body and the flow passage; means for releasably anchoring said valve body in said well tubing; means on said body for sealing between said body and the well tubing above the lateral flow passage of said body; a longitudinally movable valve sleeve disposed in said longitudinal flow passage of said body and having a longitudinal flow passage therethrough continuously open to flow through said valve sleeve, said valve sleeve being movable longitudinally in said body between a position closing the lateral port into the flow passage of the body and a position opening said lateral port; means biasing said valve sleeve in the body to a position opening said lateral port; said valve sleeve being responsive to the pressure differential exerted by the flow of fluids flowing through the sleeve, whereby a predetermined pressure differential applied to said sleeve by such fluids moves said sleeve to a position closing said lateral port; and sealing means in said flow passage of said body below said lateral port and engaging said valve sleeve for sealing therebetween to direct fluids through the flow passage of the sleeve.

6. A well control device of the character set forth in claim 5, including means removably mounted in said lateral port of said valve body restricting flow of fluids through the flow passage of said body.

7. A well control device of the character set forth in claim 5, including: means removably mounted in the flow passage of the valve sleeve for restricting flow of fluids through such flow passage to create a predetermined pressure differential across said valve under predetermined conditions of flow in the well.

8. A well control device of the character set forth in claim 5 wherein the means biasing said valve sleeve to position opening the lateral port in the body comprises a helical spring surrounding said sleeve and engaging at one end the valve body and at the other end a member adjustably mounted on the sleeve for varying the force exerted on the valve sleeve on said spring, whereby the valve member is moved to its open position opening the lateral port into the valve body when the pressure differential across the valve member due to the flow of well fluids therethrough drops below a predetermined value impressed on the spring.

9. A well control device of the character set forth in claim 5 including an elongate tubular member surrounding the valve sleeve and connected at its upper end with the valve body and extending a substantial distance below the body and open at its lower end for receiving fluids from the bore of the well tubing a substantial distance below the lateral port in the valve body.

10. A well control device of the character set forth in claim 5 wherein the valve body is provided with a valve seat in the flow passage therethrough positioned above the lateral port in said body, said seat being engageable by the valve sleeve upon movement of said valve sleeve upwardly into engagement therewith to close off flow inwardly through said lateral port into the flow passage of the body, said flow passage of said valve sleeve remaining open to permit flow therethrough while said sleeve is engaged with said seat.

11. A well control device of the character set forth in claim 9 wherein a strainer member is mounted on the lower end of said tubular extension for straining solid matter out of the fluids admitted from the well tubing into said tubing member for flow through said valve body.
